CLAIM

The ornamental design for a beverage container lid, as shown and described.

DESCRIPTION

FIG. 1 is a top perspective view of a beverage container lid, showing our new design;

FIG. 2 is a bottom perspective view thereof;

FIG. 3 is a right side elevation view thereof;

FIG. 4 is a rear elevational view thereof;

FIG. 5 is a left side elevational view thereof;

FIG. 6 is a front elevational view thereof;

FIG. 7 is a top plan view thereof; and,

FIG. 8 is a bottom plan view thereof.

The broken lines illustrate portions of the beverage container lid that form no part of the claimed design.

1 Claim, 6 Drawing Sheets
